UNITED STATES PATENT OFFICE.

WILLIAM J. DEMMING, OF CLEVELAND, OHIO, ASSIGNOR TO THE AMERICAN MULTIGRAPH COMPANY, OF CLEVELAND, OHIO, A CORPORATION OF OHIO.

DELIVERY MECHANISM FOR EMBOSSED MACHINES.

Application filed November 14, 1923. Serial No. 674,649.

To all whom it may concern:

Be it known that I, WILLIAM J. DEMMING, a citizen of the United States, residing at Cleveland, in the county of Cuyahoga and State of Ohio, have invented a certain new and useful Improvement in a Delivery Mechanism for Embossing Machines, of which the following is a full, clear, and exact description, reference being had to the accompanying drawings.

This invention relates to mechanism for delivering printing strips from a forming machine therefor onto a suitable blanket adapted to hold the same for printing. My delivery mechanism is designed to be mounted on and cooperate with an embossing machine adapted to emboss printing characters on strips of metal which are flanged inwardly at their edges and delivered by suitable rolls. My mechanism is correlated with such embossing machine so that it may operate automatically to advance such delivered strip onto a suitably held blanket mounted about a drum and intermittently fed to bring a new line of strip holding means into registration with such delivery mechanism.

An embossing machine with which my delivery mechanism may cooperate is shown, described and claimed in the application of Clifton Chisholm, No. 535,311, filed February 9, 1922, and so much of such embossing machine as directly cooperates with my delivery mechanism is shown in the present application.

Certain features of the present delivery mechanism are also shown and claimed in a prior application of mine, No. 583,192, filed August 21, 1922, which provides for the manual delivery of embossed strips onto a flat address plate. Certain other features of the present mechanism are shown and claimed in an application of Clifton Chisholm, No. 583,188, filed August 21, 1922, illustrating a manual means for feeding strips onto a curved blanket mounted on the drum, and manual means for moving the blanket step by step to present a new line. My mechanism is an improvement on the Chisholm mechanism just mentioned, among other features in that it operates automatically both to move the strip onto the blanket and to move the blanket for a new line.

It should also be noted that the blanket shown herein, comprising a plate having

rows of raised and connected buttons over which embossed strips may extend, the inwardly flanged edges of such strips projecting beneath the button heads, is covered in Patents Nos. 1,438,580 of Clifton Chisholm, 60 1,438,584 of myself, and 1,438,582 of B. J. Craig, all issued December 12, 1922.

In the drawings of the present application, Fig. 1 is a plan of my delivery apparatus attached to an embossing machine of the type illustrated in the application of Clifton Chisholm, No. 535,311, referred to; Fig. 2 is a front elevation of my delivery apparatus accompanied by a vertical section through such embossing apparatus; Fig. 3 is a sectional end elevation of such embossing apparatus, as indicated by the line 3-3 on Fig. 1; Fig. 4 is a vertical section on a larger scale through the embossing apparatus, as indicated by the line 4-4 on Fig. 70 1; Fig. 5 is a vertical section at right angles to Fig. 4, as indicated by the line 5-5 on Fig. 4; Fig. 6 is a detail illustrating the sliding pusher for moving the embossed strip toward the delivery mechanism, being 75 a section on the line 6-6 on Fig. 5; Fig. 7 is a sectional plan of my delivery mechanism; Fig. 8 is a front elevation of my delivery mechanism; Fig. 9 is a detail thereof, being a section on the line 9-9 on Fig. 8; Fig. 10 is a vertical section of my delivery mechanism, as indicated by the line 10-10 80 on Fig. 7; Fig. 11 is a sectional elevation of a portion of my delivery mechanism, the plane of the section being indicated by the 90 line 11-11 on Fig. 10, the view being taken looking toward the front; Figs. 12 and 13 are details of the mechanism for feeding and locking the blanket onto which the strips are fed, being vertical sections on the 95 correspondingly numbered lines on Fig. 7; Fig. 14 is a sectional plan of such feeding and locking mechanism, as indicated by the line 14-14 on Figs. 10 and 12; Fig. 15 is a 100 segregated perspective of the sliding mechanism which carries the embossed strip from the delivery rolls to the blanket; Figs. 16 and 17 are diagrammatic views illustrating different positions of the strip engaging mechanism; Fig. 18 is an elevation of the clutch mechanism for controlling the delivery mechanism, being an enlarged view of a portion of the mechanism shown in Fig. 3, looking in the opposite direction; Fig. 19 105 is another view illustrating the clutch 110

mechanism, being a section on a plane at right angles to the plane of Fig. 18, as indicated by the line 19—19 on Figs. 3 and 18; Fig. 20 is a horizontal section through the clutch mechanism, as indicated by the line 20—20 on Figs. 2 and 18; Fig. 21 is an elevation of the shift mechanism shown at the left hand side of the keyboard of the embossing machine; Figs. 22 and 23 (Sheet 9) 10 are respectively enlarged fragmentary perspectives of the embossed strip and the receiving blanket therefor; Fig. 24 (Sheet 6) is a horizontal section through the delivery rolls and adjacent rail, as indicated by the line 24—24 on Fig. 8.

In order that my delivery apparatus may be better understood I will first describe briefly the embossing machine illustrated in Figs. 1 to 5 inclusive, though it is to be 20 understood that my invention is not limited to coaction with that particular type of embossing machine.

The embossing machine shown comprises a reciprocable die carrier 10, having individually movable male and female dies 11, a keyboard 12, and suitable mechanism controlled by the keyboard for positioning the die carrier and consequent upon such positioning automatically plunging the selected 30 dies toward each other to emboss an intermediate strip 13 which is fed from a suitable reel 14 and flanged at its edges by intermittently operated rolls 15. Such flanged strip passes along a supporting rail 16 behind a retaining rail 17, both extending through an open longitudinal space in the die carrier. These rails are cut away at the central portion 18 where the selected dies 35 operate to effect the embossing.

40 To reciprocate the die head of this Chisholm embossing machine there are provided a pair of solenoids 20 operating on a common core bar 21 connected by a link and lever 22 with the die head, the solenoid on either side being energized whenever a key in the corresponding half of the keyboard is depressed. The die carrier, thus shifted from its central position of rest, is stopped in selected position by means of the 45 raised rear end of the key lever 25, which coacts with a suitable latch on the die carrier. Fig. 5 shows the raised rear end of the shearing key lever 26, hereinafter more fully described, which in this respect acts 50 similarly to an embossing key lever.

As the die carrier moves toward such raised rear end of an actuated key lever, the plunger 30, having an inclined lower end, engages the key lever and is raised thereby 60 to actuate the plunging mechanism about to be described. After this plunger 30 passes over the key lever, the die carrier is stopped by engaging the resilient abutment 32 and then the plunger 30 descends to rest 65 behind the key lever, so that the die carrier

becomes locked in a definite position with the dies corresponding to the actuated key in the central or embossing position.

The raising of the plunger 30 swings a bale 35, which by means of a link 36 and a bell crank 37 withdraws the rod 38 from a single-rotation clutch 40. This clutch, thus freed, clutches the continuously rotating main driving pulley 47 to the shaft 41, which carries a pair of crown cams, indicated at 42 in Fig. 2, which operate on the lower end of intermediately pivoted levers 43 and 44, which act to shove inwardly suitable plungers 45 and 46, which engage the outer ends of the selected female and male dies respectively, or the shearing dies 48 and 49 shown in Fig. 4.

Following the embossing operation the plunging mechanism returns to normal position, spring fingers 50 on the die head return the dies, the key returns, the circuit to the energized solenoid is opened and the carrier is returned to normal position under the influence of a compression spring on either side of the carrier, one of these springs being illustrated at 51 in Fig. 4. During these return operations the strip is fed toward the right a distance of one character by means of the rolls 15. As shown one of these rolls carries a ratchet 52 operated by a pawl 53 on a suitable lever connected by a link 54 with a rock arm on the rock shaft 55, which also carries the die operating lever 43.

The mechanism for returning the key levers, shown in Fig. 4, comprises a hook 60 on the embossing lever 43, which on the return or outward stroke engages the upper end of a pivoted latch plate 61, the lower end of which extends beneath a tooth 62 on a raised key lever. When this lower end is withdrawn the key lever is freed and the lever is suitably returned.

Figs. 1 and 4 indicate at 65 levers for closing the solenoid switches when a key is depressed. Each of these levers carries a rod 66 overhanging upward extensions 67 on the rear portions of the key levers. Fig. 4 illustrates also suitable mechanism for normally locking the die head in central position, comprising a central gib 70 on the die head adapted to stand between the upper ends of two levers 71 and 72 pivoted at 73 and each carrying at its forward end a universal bar, 74, 75, which extends over all of the key levers in that half of the keyboard. The actuation of any key thus releases the die carrier before the solenoid acts to move the die carrier.

Fig. 4 illustrates also mechanism whereby the space key may release the clutch without releasing the die head, resulting in feeding of the metal strip without embossing. Thus the space bar 80, Fig. 1, is mounted on levers, one of which 81 carries at its rear

end a dog 82 which extends beneath the bell crank 37 connected to the clutch rod 38 heretofore mentioned. When the space key is depressed the dog 82 is raised initiating the 5 operation of the clutch; then the dog immediately passes out of engagement with the bell crank by reason of the pin 86, and the spring 85 returns the clutch rod to stopping position.

10 90 in Figs. 1 and 21 indicates a shearing key located at the keyboard on the forward end of the key lever 26. This key lever operates to shift the die head and stop it and initiate the operation of the clutch the 15 same as already described for the character keys. The shearing dies are shown at 48 and 49 in Fig. 4. When they are brought into position, and the clutch operated, the embossing levers 43 and 44 operate to plunge 20 these dies toward each other. The die 49 has notches to receive the edges of the flanged strip, and the die 48 operates to shear first through the corners of the strip and then the body of the strip, thus cutting 25 out a short section and leaving free the embossed line strip indicated at 92 in Fig. 2.

It will be seen from an inspection of Fig. 5 that the shearing die 48 there shown is of materially less height than the character 30 dies 11. This is because in this embodiment each character die has three related faces (lower case, upper case, numerals and punctuation) controlled by a shift mechanism. The shearing dies are positioned 35 corresponding to the lower case characters on the character dies. It is accordingly desirable that whenever the shearing die is about to be operated the shift mechanism be automatically operated to carry the die head to 40 lower case position, if it is not already in that position.

Mechanism for the above purpose is illustrated in Figs. 1, 2 and 21, wherein 100 indicates a shift lever connected with the die 45 head to raise it, the lever having two arms, 99 connected to vertical slides, 98 carrying a horizontal rod, 97 on which the die head travels. 101 and 102 are respectively slideable and fixed keys adapted to push the lever 100 down a certain distance to shift the die head one step, or twice that distance to shift it two steps, according to whether the stem 103 of the key 101 or the shorter abutment 104 limits the movement 50 by striking against a stationary abutment 105. The key stem 103 is slideable through the lever so that the latter may continue to descend when the key 102 is pressed. The shift key is held in either of the depressed 55 positions by a toothed latch 107 drawn toward it by a spring 108. This specific mechanism is the invention of Clifton Chisholm and will be covered by an application about to be filed by him.

60 65 The position of the shift key lever 100

shown in Fig. 21 is the lower case position of the character dies and the active position of the shearing dies. To insure the die head being in that position when the shearing key is operated, I attach a link 110 to 70 the shearing key lever and connect it to a rock arm 111 on a rock shaft 112 which carries an arm 113 adapted to engage a shoulder 114 on a pivoted arm 115, the upper end of which has a fork and pin connection with the latch 107. The result is that whenever the shearing key is depressed the latch 107 is swung forwardly, releasing the shift lever, and accordingly if that lever happens to be in either of its depressed 80 positions this frees the die head and allows it to drop by gravity to its normal or lower case position.

The operation of the shearing key described initiates the operation of my delivery mechanism which will now be described with reference first to Figs. 1, 2, 3, 5, 6, 18, 19 and 20.

On the rock shaft 112 above mentioned in connection with the shift key is an arm 90 120 connected by a link 121 with a lever 122 pivoted at 123. The other end of this lever carries a depending rod 124 which has a shoulder 125. When the shearing key is depressed to effect the shearing, the bar 95 124 is simply raised idly. Following the shearing, however, on the return stroke of the shearing key, the bar is depressed by the spring 126 and the shoulder 125 on the bar 100 engages a pivoted arm 130 which carries a block 131 normally engaging a lug 132 on a dental clutch collar 133. The withdrawal of the block 130 by the depression of this arm frees the clutch collar and thereupon a spring 135 acting on the shipper 105 lever 136 throws the clutch collar into engagement with the mating member 137 on the hub of the continuously rotating gear 139 loose on the shaft 140. This gear 139 is continuously rotated by any suitable 110 means. As shown it meshes with a pinion 150 on a shaft 151 which carries a pulley 152 belted to a pulley 153 on the main clutch shaft 41.

When the dental clutch just described goes 115 into engagement the shaft 140 makes one rotation. At the end of the rotation the lug 132 acting on the beveled face 143 of the block 131 withdraws the clutch member 133 from engagement, restoring the parts. The thrust on the arm 130 in this action is received by the stationary bracket plate 138.

In setting the clutch as above described, when the shipper lever 135 shifts the clutch 120 collar, a bracket 145 on the shipper lever 125 engages a pin 146 on the depending link 124 and thereby swings it against the action of the spring 147 to clear the depressed arm 130, and thereupon the spring 149 returns 130 that arm to normal position, bringing the

block 131 into position to engage the clutch lug 132 as above described.

It will be seen from the above description that whenever the shearing key is operated a small section is sheared out of the embossed strip, and then, as the plunger mechanism, die head and shearing lever are being restored to normal position the shearing lever, through the mechanism last described, effects the engagement of the dental clutch to cause a single rotation to the normally idle shaft 140. This shaft, through mechanism which will now be described, operates to shift the embossed and sheared strip from its position within the die head toward the right of the machine.

The single rotation shaft 140 above mentioned is mounted in a U-shaped frame casting 160, Figs. 2, 19 and 20. Pinned on this shaft are two cams 161 and 162. The cam 161 coacts with a roller 164 on a link 165 connected to a lever 166, which is connected by a link 167 with the sliding plate 168, as hereinafter described, and is adapted to engage the sheared off portion of the strip and then move toward the right under the control of the cam 161 to shove such embossed strip.

Referring to Fig. 2, it will be seen that the first operation of the cam 161 is by reason of its suddenly increasing face 169, which, acting on the roller 164, carries the plate 168 to its extreme left hand position. Then, as a portion of the cam of decreasing radius coacts with the roller 164, a spring 170 swings the lever 166 toward the right and thus shoves the plate 168 in that direction. The plate 168 is pivoted at 169 to a sliding bar 173 which occupies a horizontal slideway 174 in the stationary frame rail 16. A spring 175 on the sliding bar 173 bears against the stationary rail 16 and forces the plate against the mating stationary frame rail 17. This makes a frictional drag on the pivot of the plate so that when the plate moves toward the left in its initial positioning, the link 167 drawing it rocks it upwardly a slight distance until the roller 177 carried by the plate engages the top of the stationary rail 17. Now, when the spring 170 acts to shove the plate 168 toward the right the reverse rocking takes place until the roller 178 on the plate engages the rail 17. This swings the nose 179 of the plate downwardly so that it digs into the section of the strip which was cut off by the shearing dies. Then as the spring 170 continues to move the plate 168 toward the right the engaged strip is shoved with it into the pass of the delivery rolls 180.

The delivery rolls 180, Figs. 1, 2, 7 and 8 are continuously rotating quite rapidly, and operate as soon as they receive the embossed strip 182, Fig. 2, to force it through the roll pass and deliver it into the stationary T rail

192. These rolls, it will be understood, not only feed the strip but bend inwardly the edge flanges thereof; that is to say, they transform it from the parallel-edged shape shown in section at 92 in Fig. 4 into the shape shown at 182 in Fig. 22, wherein the two edge flanges 183 will be seen to converge.

As shown the continuously rotating delivery rolls 180 are rotated by means of the continuously rotating gear 139 heretofore described. As shown in Figs. 2 and 3, this gear meshes with an idler 185 which meshes with a pinion 186 on a shaft carrying a bevel gear, 187. This gear meshes with a bevel gear 188 on a shaft 189, on the upper end of which is one of the delivery rolls 180. The other delivery roll 180 is geared with this roll to rotate at the same speed and opposite direction by intermeshing gears, of which one is shown at 190 in Fig. 2.

While the cam 161 on the shaft 140 was acting, as above described, to shove the embossed strip toward the right and into the pass of the delivery rolls, the cam 162 was acting to shove toward these delivery rolls the slide mechanism to engage the delivered strip. As shown, this cam 162 acts between two rollers 200 and 201 on a link 202 connected to a lever 203, the upper end of which is connected by a link 204 to the sliding mechanism 205, which carries at its upper end a pivoted hook member 206 adapted to engage the delivered strip. The cam 162 is heart-shaped and formed to substantially contact at all times with each roller 200 and 201. As it starts to rotate, its increasing radius acting on the roller 200 shifts the slide mechanism toward the left until the hook member 206 thereon, by mechanism hereinafter described is in position to engage the delivered strip at its left hand end. Then as the portion of the cam of decreasing radius coacts with the roller 200, the correspondingly increased portion, bearing against the roll 201, shoves the slide mechanism toward the right rocking the hook and carrying with it the delivered strip and shoving it onto the receiving blanket 210.

The blanket as shown in Fig. 23 comprises a sheet metal plate having longitudinal rows of round buttons 211 stamped up from it so as to be separated from it at their edges, while intermediately the buttons are connected to the plate and are further connected with each other by raised corrugations 212. A plate is thus provided which makes a continuous support for the embossed strip 182 and at the same time has overhanging shoulders beneath which the curved in edges 183 may extend. Such blanket is covered in patents to Clifton Chisholm, B. J. Craig and myself, Numbered 1,438,580, 1,438,582 and 1,438,584 respectively, already mentioned.

The blanket 210 described is mounted on a suitable drum-like form. As shown in Fig. 10, 220 indicates a segmental drum on a shaft 221. This drum is provided with T-5 rails 222. The extreme edges of the blanket are rolled inwardly as shown at 215 and 216. One of these rolled ribs is adapted to extend between any convenient adjacent rails 222. The other rib occupies a channel in a plate 10 225 on an arm 226 loosely journaled on the shaft 221. Set screws 227 carried by this arm and bearing against the edge of the drum segment 220 operate to pull the blanket away from such segment, tighten it about 15 the drum, and hold it in place.

Suitable mechanism hereinafter described locks the drum in position and periodically feeds it step by step to position a new row of buttons 211 in alignment with the rail 20 192 which carries the delivered strip. The shaft 221 which carries this drum is mounted in suitable brackets 230 and 231 secured to a suitable frame casting 234 which is secured to the main frame of the embossing machine 25 and carries not only the drum described but the slide mechanism which I will now describe.

The slide mechanism referred to as 205 includes a slide 240 slidable on a horizontal 30 rod 241 and having ears 242 by which it is pivotally connected to the link 204 leading from the cam operated lever 203. The slide 240 has a flat top plate 244 on which rests a transversely extending flat rocking bar 250 carrying a pin 251 depending into a notch 252 in the top plate of the slide.

The transverse bar referred to is housed within a recess 255 in the lower face of a standard 256 which is slidable upon the 40 frame rod 257 and the frame plate 258. This standard carries the vertical rock shaft 260, which at its lower end is pinned to the rocking bar 250 and at its upper end adjustably but tightly carries the hook 206.

As the slide 240 moves toward the left under the influence of the cam 162, the right hand wall of the notch 252 (left hand in Figs. 11, 15, 16 and 17) engages the pin 251 depending from the rocking bar 250, and thus carries the rocking bar, standard and hook toward the left until the point of the hook is beyond the left hand end of the delivered strip.

To carry the strip from the delivery rolls into position so that the point of the hook in its left hand position will be beyond it, I provide a horizontally sliding hook 270, Figs. 7 and 24, which extends freely through the pass of the roll 180 and has its right hand portion 273 guided in a slideway in the horizontally stationary member 274 which carries the rail 192 for supporting the strip. This rail is slotted horizontally at 276 to receive the hook 270. This hook member is 55 pivoted at its right hand end to the lever 271

which is intermediately pivoted to a link 272 and depends below its pivot into the path of a lug 275 on the forward edge of the top plate of the slide 240. Accordingly, as the slide mechanism is carrying its hook 206 toward the left it is also, through the intermediately pivoted lever 271, moving the hook 270 toward the right, thus drawing the finished strip onto the rail 192, as shown in Fig. 24. Thus, as the slide mechanism reaches its left hand position the point of the hook 206 is beyond the left hand end of the delivered strip.

The hook is adjustable on the shaft 260 so that when it rocks inwardly to its limit as 80 hereinafter described, it overhangs the end of the embossed strip but it does not engage the supporting rail 192 behind it and will not subsequently engage the blanket. The adjustment of the hook plate 206 with reference to the rod 260 is readily effected by loosely journaling the hook plate on the rod above a collar 282 pinned to the shaft. Suitable set screws 283 pass through arcuate 85 slots 284 in the hook plate and thus clamp 90 it in place for the desired adjustment, after which the parts are jammed by a nut 285 screwing onto the top of the shaft 260.

As hereinafter explained, the hook 206 stands normally swung to the front away from the embossed strip. When the movement to the left begins the notch 252 catches up to the pin 251 as heretofore explained. Thereafter, during the travel of the slide mechanism toward the left the latching bolt 290 which slidably occupies the notch 291 in the rocking bar 250 is released as hereinafter explained and moves downwardly under the influence of the spring 292 into the notch 252. It will be noticed that this notch is enlarged at this point 296 so that there is play of the lower end of the latching bolt in the notch. This is the normal condition as the slide mechanism moves toward the left. It comes to rest with the hook 206 beyond but 95 in front of the left hand edge of the embossed strip. Now on the return movement the first thing that takes place is for the slide 240 to take up the slack between the left hand or trailing edge of the slot 252 and the latching bolt 290 and rock the rocking bar until it is stopped by abutting the pin 280, the parts thus coming into the position 100

105 shown in Fig. 16. The parts remain in this condition during the right hand movement of the slide mechanism until the strip is drawn onto the blanket, it being understood that one of the rows of blanket buttons 211 is held in alignment with the rail 192 so that as the slide mechanism moves toward the right under the influence of the cam 162 the engaged strip is drawn along the slide 110 and onto the blanket.

When the embossed strip reaches its final 115 position on the blanket as shown in Figs. 8 125 and 9 the slide mechanism is returned to its 130

- and 11 its far end engages a bell crank 300, which is rocked thereby and thus moves downwardly the horizontal plate 302, this plate having a parallel-ruler connection 5 with the stationary plate 303 by means of the portion 304 of the bell crank and a parallel and equal-length link 305. This plate remains in its lowered position until eventually released and returned by a spring 306. 10 This downward movement of the plate 302 causes it to engage a roller 310 on the free end of a lever 311, the other end of which is connected to the latching bolt 290. This results in raising the bolt and thereby temporarily unlocking the hook carriage from the slide. As soon as this takes place a slight further movement toward the right of the slide 240 brings the pin 246 against the stop 247 as shown in Fig. 17, and therefore 15 the continued movement of the slide and carriage allows the hook to swing forwardly away from the embossed strip, and the rest of such movement of the slide mechanism is idle. 20 By the means described, I am enabled to make the travel of the slide mechanism sufficient to shove the shortest line onto the blanket; at the same time, irrespective of the length of the line, the hook swings out 25 of engagement with the left hand end thereof when the right hand strikes the stop 300. 30 To enable the right hand end of the strip to stop at different points to provide for 35 the beginning of paragraphs (such right hand edge of the blanket corresponding to the left hand side of the paper printed) I mount the stop 300 so that it may be manually shifted horizontally and lock in any 40 described position, and irrespective of its position perform the stopping and releasing function heretofore described. This manual positioning of the stop 300 is effected as follows: 45 Referring to Figs. 1, 2 and 8, it will be seen that the stopping bell crank 300, the movable plate 302 and the normally stationary plate 303 are all carried by a slideable carriage 320, this standard being slidably mounted on the stationary plate 258 and also on a stationary rod 321 parallel therewith. A link 323 connects this carriage 320 with a manual lever 324 which is pivoted at 325 and carries near its free end 50 a lip 326 engaging teeth on a stationary segment 327. The elasticity of the lever 324 is sufficient to allow the lip to slide over the ratchet teeth toward the right in Fig. 1 when it is desired to move the stop carriage toward the left. It will then remain in 55 this set position until the lever 324 is slightly raised and swung back manually toward the left into some desired new position. 60 As heretofore alluded to, the drum 220

which carries the blanket is normally locked into position, but following the placing of an embossed strip on the blanket, the blanket is automatically given a partial rotation sufficient to bring a new row of strip holding buttons 211 into registration with the strip rail 192. The mechanism for effecting this will now be described with particular reference to Figs. 1, 2, 7 to 14 inclusive, and 23. 75

The blanket shown in Fig. 23, and claimed in the patent to B. J. Craig above mentioned, has outward corrugations 212 between the buttons which stiffen the plate in the direction of the buttonrow and form a support for the embossed strip between the buttons. The groove on the rear of the blanket caused by this corrugation is utilized to index the blanket and maintain proper registration with the external strip holding rail. This feature is claimed in the application of Clifton Chisholm above mentioned. 80 85

Figs. 12, 13 and 14 show at 340 a bevel nosed snubbing pin pressed toward the blanket 210 by a spring 341, this pin and spring being mounted in a stationary (though adjustable) bracket 342 which is loose on the drum shaft 221. The bevel nose of this pin engages in the rearwardly facing groove caused by the corrugation 212 of the blanket and by reason of its beveled face and the inclination of the walls of the groove accurately centers the blanket. This snubbing pin forms a lock of sufficient force not only to accurately center the bracket but to hold it normally in registration. When, however, the drum is given a partial rotation to present a new row of buttons the blanket simply snubs over the pin which is thereby cammed inwardly against its spring 341. 90 95 100 105

To cause the point of the snubbing pin 340 to be accurately in position with reference to the external rail 192 I make the bracket 342 adjustable within slight limits. I effect this by making a notch 350 in a downwardly extending leg 345 of the bracket, and in this notch I mount an eccentric 351 on a short shaft 353 which is journaled in the adjacent bracket 230 in which the drum shaft 221 is journaled. A screw driver notch 355 in the end of this shaft 353 provides means for turning it and a lock nut 356 jams it in accurate position. 110 115 120

To turn the drum step by step automatically I provide a disk-like collar 360 pinned to the shaft, and cooperating with this is a roller 361 mounted between it and an abutment block 362 carried between and secured to plates 363 and 364 which are loose on the shaft. The face 365 of the abutment block adjacent the collar 360 is inclined downwardly toward that collar and the roller is pressed toward the restricted opening thus 125 130

provided by a spring 367. The roller thus tends to clutch the collar, shaft and drum to the oscillating plates 363 and 364, and accordingly one of those plates may furnish 5 means to give the desired partial rotation to the drum.

I extend the plate 363 toward the front where it overlies and rests on a bell crank 370 connected by a link 371 and a spring 10 373 connected by a bell crank 372. The end portion of the link is slotted at 378 about a pin 379 on the bell crank. The spring anchored to the link and the pin normally maintains the pin against the left hand end 15 of the slot and the bell crank against the stop pin 374. This bell crank 372 carries at its free end a pivoted cam dog 375 shown in Figs. 8 and 9. This dog has a rearwardly extending lip 376 which overhangs the 20 substantially horizontal arm 377 of the bell crank 372 and supports the dog in position so that it extends diagonally above and below the path of a pin 378 projecting rearwardly from the bearing portion 25 of the slide 240. Now when the slide mechanism heretofore described is moving toward the right to carry the embossed strip onto the blanket, the pin 378 engages beneath the cam dog 375 and lifts it idly and 30 travels beyond it. On the return movement of the slide mechanism this pin 378 engages the inclined top surface of the cam dog 375 and cams it and the bell crank arm 377 downwardly as the slide mechanism travels 35 toward the left. This pulls on the link 371, rocking the bell crank 370, raising the plate 363, and thereby rocking the drum to bring a new line of buttons on the blanket into receiving position. The parts thus come 40 into the position shown in Fig. 8.

If, through inadvertence, the embossed strip is longer than the available space on the blanket, so that it lies partly on the blanket and partly on the rail 192, no damage is done, as the spring 373 yields and the bell crank pin 379 moves idly in the slot 378 in the link 371.

Suitable springs as 380 and 373 operate to return the plate 363 and the link 371 50 and its connected parts to normal position when the pin 378 clears the cam dog 375. This restores these parts to normal position ready for another operation subsequent to the delivery of the next strip.

The movement of the drum in the operation described is accurately limited, preventing any overthrow by momentum, by means of a pair of set screws 385, Figs. 8, 12 and 14, which engage a pin 386 carried by the 55 plate 363. For convenience I have mounted these set screws in the depending leg 345 of the normally stationary standard 342.

As it is sometimes desired to skip one or more lines on the blanket, I provide a 60 manual device for rotating the drum, which

may also be availed of to set the blanket originally to bring the desired region thereof into receiving position. This manual mechanism comprises simply a hand lever 390 projecting forwardly from the upper 70 portion of the plate 363 and furnishing means for rocking it as desired.

To allow the drum to be turned backwardly manually, I provide a releasing lever 391 pivoted on the plate 363 and having 75 an upwardly turned end 394 which normally stands just beneath the roller 361. By depressing the forward end of this lever the roller may be raised to unclutched position, thereby freeing the drum and allowing it to be turned by hand as desired backwardly, as well as forwardly, the snubbing pin springing into the successive groove as the blanket travels, and stopping it accurately in any registering position in 80 which it may be left.

To enable the blanket to be readily placed on the drum, I provide means for locking the snubbing pin 340 inwardly in idle position. This means is illustrated particularly 90 in Figs. 13 and 14 and comprises a plate 400 pivoted to the horizontal arm of the bracket 342 and normally held in its upward position by a spring 401. This plate has an opening 402 with a cam edge 403. Extending idly into this opening is a pin 405 carried by the snubbing pin 340. The opening is of sufficient size so that in the ordinary operation the pin 405 moves idly in the opening. When, however, the plate 400 is rocked downwardly (as may be readily done manually by the operator engaging with his finger the turned over end 407 of the plate), the inclined wall 403 engages the pin 405 and withdraws the snubbing 100 pin into idle position. It remains in this position by reason of the spring 341 forcing the pin 405 against the portion 408 of the opening wall, which inclines slightly away from the center. The parts may be 105 readily restored whenever desired by a slight upward pressure on the lip 407.

It is sometimes desirable to deliver the embossed strip from the embossing machine onto the blanket manually. To effect this readily without interfering with the automatic operation described, I provide a hand wheel 410 on the forward end of the shaft 140. This wheel normally rotates idly whenever the shaft 140 rotates. It furnishes means, however, whereby this shaft may be rotated by hand whenever desired and thus carry out the same operations as heretofore described when the dental clutch (shown in Figs. 3, 19 and 20) is engaged and this shaft rotated by means of the continuously rotating gear 139.

To prevent the dental clutch, controlling the automatic operation, from going into engagement during the hand operation, I pro- 130

vide the locking out mechanism shown in Figs. 3 and 19; that is to say, I connect to the upper end of the link 136 a link 415 which leads forwardly and has its free end 5 portion supported and guided by a stationary stirrup 416. Ordinarily this link 415 plays idly through the stirrup. The link, however, is provided with a notch 417 at its upper edge and a lip 418 on its forward end. 10 When the link is drawn forwardly by this lip and lifted, its notch embraces the stirrup plate at the top of the slot therein and thus holds the link elevated by friction, and this holds back the movable clutch member 133, 15 enabling the hand operation by the hand wheel 410 as long as desired. A sufficient downward pressure, however, on the lip 418 releases this lock-out mechanism whenever desired. 20 To enable the delivery mechanism to operate without requiring the operation of the shearing mechanism so that the drum may be indexed idly (as for instance when composing "double-space" matter) I provide an 25 extra key 450 at the side of the key-board (Fig. 1) which has a shank extending downwardly and connecting with the forward end of the lever 122 (Fig. 3). The connection of the lever 122 with the shearing key is 30 by a pin and slot as shown in Fig. 3, so that when the lever 122 is operated by the key 450, the shearing key is not operated thereby. This allows the dental clutch controlling the automatic indexing to be independently initiated whenever desired. 35 The indexing by the key 450 just described will ordinarily be done immediately following the delivery of a strip onto the blanket and before the subsequent strip is embossed. If, however, the operator delays 40 the idle indexing until after he has embossed the subsequent line or a material portion of it, the toe 179 of the shoving plate 168 will stick in such embossed line or portion which 45 it cannot feed, the spring 170 yielding idly. To prevent damage to the machine in case 50 such sticking occurs while the plate 168 is overlapping the embossing opening 18 I provide the safety mechanism shown in Figs. 2, 4 and 5. This mechanism comprises 55 a slotted link 420 loosely connected to the lever 166, which operates the plate 168, and pivoted at its other end to the lower end of a rock lever 421. The upper end 422 of this lever extends adjacent to a collar 423 on the clutch operating rod 38. Ordinarily this lever portion 422 is held out of registration with the collar by a spring 424 as shown in 60 Figs. 2 and 5. Now if the plate 168 should stand in registration with the opening 18, then the lever 166 will pull the rod 420 toward the left in Fig. 2, rocking the lever 421 so that its upper end 422 stands in front of the collar 423. In such condition, when 65 the rocking plunger 30 on the die head rises

from engagement with the key lever and tends, through the bale, link and bell crank mechanism heretofore described, to withdraw the clutch rod, such operation is non-effective, because the clutch rod is locked. 70 Therefore the lower end of the bell crank 37 simply compresses a stiff spring 425 which, as shown in Fig. 4, positions a slideable head 426 into which the lower end of the bell crank 37 extends. Normally this 75 spring presses this head against a shoulder on the rod and the head acts unitarily with the rod to withdraw it when the bell crank is operated, but under the condition just described the spring forms a safety device preventing straining the parts. 80

My prior application referred to, shows a mechanism for loading delivered embossed strips onto a flat address plate. The present mechanism has been designed so that a 85 somewhat similar device for holding a flat plate may be substituted for the drum 220. To enable this to be readily effected, I mount the drum shaft 221 in upwardly opening slots in the two standards, 230 and 231, and 90 I cover the shaft at these bearings by movable retaining plates 460 adapted to release it.

As shown in Fig. 7, each retaining plate 95 460 has a notch in its rear edge extending beneath a screw 461 and has a slot 462 through which extends a clamp screw 463, which when loosened allows the plate to be slid forwardly to idle position. The sliding or removal of these plates enables the shaft, 100 with the drum and operating mechanism mounted on the shaft, to be readily removed from the standards and other mechanism substituted.

It will now be understood, from the given 105 description, that I have provided a mechanism adapted to be coupled with an embossing machine which produces embossed printing strips, and feed such strips onto a suitable receiving blanket, and that the mechanism is arranged to operate entirely automatically consequent upon the operation of the key which shears off the embossed line. As soon as such key is operated, the delivery mechanism described is initiated and 110 proceeds with its function independently of the operator, who may go on with the embossing of a subsequent line. The complete delivery of the embossed line, while sufficiently deliberate to operate smoothly, is effected well in advance of the time it will 115 take the operator to emboss a new line. Accordingly, his embossing operation proceeds without delay, and substantially as soon as he has embossed sufficient lines to constitute 120 a page form, the same are properly assembled on the blanket, and all that is necessary is to release the blanket from the drum and it is ready for use in a suitable printing machine. While this mechanism is normally 125 130

provided by a spring 367. The roller thus tends to clutch the collar, shaft and drum to the oscillating plates 363 and 364, and accordingly one of those plates may furnish 5 means to give the desired partial rotation to the drum.

I extend the plate 363 toward the front where it overlies and rests on a bell crank 370 connected by a link 371 and a spring 10 373 with a bell crank 372. The end portion of the link is slotted at 378 about a pin 379 on the bell crank. The spring anchored to the link and the pin normally maintains the pin against the left hand end 15 of the slot and the bell crank against the stop pin 374. This bell crank 372 carries at its free end a pivoted cam dog 375 shown in Figs. 8 and 9. This dog has a rearwardly extending lip 376 which overhangs the 20 substantially horizontal arm 377 of the bell crank 372 and supports the dog in position so that it extends diagonally above and below the path of a pin 378 projecting rearwardly from the bearing portion 25 of the slide 240. Now when the slide mechanism heretofore described is moving toward the right to carry the embossed strip onto the blanket, the pin 378 engages beneath the cam dog 375 and lifts it idly and 30 travels beyond it. On the return movement of the slide mechanism this pin 378 engages the inclined top surface of the cam dog 375 and cams it and the bell crank arm 377 downwardly as the slide mechanism travels 35 toward the left. This pulls on the link 371, rocking the bell crank 370, raising the plate 363, and thereby rocking the drum to bring a new line of buttons on the blanket into receiving position. The parts thus come 40 into the position shown in Fig. 8.

If, through inadvertence, the embossed strip is longer than the available space on the blanket, so that it lies partly on the blanket and partly on the rail 192, no damage is done, as the spring 373 yields and the bell crank pin 379 moves idly in the slot 378 in the link 371.

Suitable springs as 380 and 373 operate to return the plate 363 and the link 371 50 and its connected parts to normal position when the pin 378 clears the cam dog 375. This restores these parts to normal position ready for another operation subsequent to the delivery of the next strip.

The movement of the drum in the operation described is accurately limited, preventing any overthrow by momentum, by means of a pair of set screws 385, Figs. 8, 12 and 14, which engage a pin 386 carried by the 55 plate 363. For convenience I have mounted these set screws in the depending leg 345 of the normally stationary standard 342.

As it is sometimes desired to skip one or more lines on the blanket, I provide a 60 manual device for rotating the drum, which

may also be availed of to set the blanket originally to bring the desired region thereinto receiving position. This manual mechanism comprises simply a hand lever 390 projecting forwardly from the upper 70 portion of the plate 363 and furnishing means for rocking it as desired.

To allow the drum to be turned backwardly manually, I provide a releasing lever 391 pivoted on the plate 363 and having 75 an upwardly turned end 394 which normally stands just beneath the roller 361. By depressing the forward end of this lever the roller may be raised to unclutched position, thereby freeing the drum and allowing it to be turned by hand as desired backwardly, as well as forwardly, the snubbing pin 340 springing into the successive groove as the blanket travels, and stopping it accurately in any registering position in 85 which it may be left.

To enable the blanket to be readily placed on the drum, I provide means for locking the snubbing pin 340 inwardly in idle position. This means is illustrated particularly 90 in Figs. 13 and 14 and comprises a plate 400 pivoted to the horizontal arm of the bracket 342 and normally held in its upward position by a spring 401. This plate has an opening 402 with a cam edge 403. Extending idly into this opening is a pin 405 carried by the snubbing pin 340. The opening is of sufficient size so that in the ordinary operation the pin 405 moves idly in the opening. When, however, the plate 400 is rocked downwardly (as may be readily done manually by the operator engaging 95 with his finger the turned over end 407 of the plate), the inclined wall 403 engages the pin 405 and withdraws the snubbing 100 pin into idle position. It remains in this position by reason of the spring 341 forcing the pin 405 against the portion 408 of the opening wall, which inclines slightly away from the center. The parts may be 105 readily restored whenever desired by a slight upward pressure on the lip 407.

It is sometimes desirable to deliver the embossed strip from the embossing machine onto the blanket manually. To effect this 115 readily without interfering with the automatic operation described, I provide a hand wheel 410 on the forward end of the shaft 140. This wheel normally rotates idly whenever the shaft 140 rotates. It furnishes means, however, whereby this shaft may be rotated by hand whenever desired and thus carry out the same operations as heretofore described when the dental clutch (shown in Figs. 3, 19 and 20) is engaged 120 and this shaft rotated by means of the continuously rotating gear 139.

To prevent the dental clutch, controlling the automatic operation, from going into engagement during the hand operation, I pro- 130

vide the locking out mechanism shown in Figs. 3 and 19; that is to say, I connect to the upper end of the link 136 a link 415 which leads forwardly and has its free end 5 portion supported and guided by a stationary stirrup 416. Ordinarily this link 415 plays idly through the stirrup. The link, however, is provided with a notch 417 at its upper edge and a lip 418 on its forward end. 10 When the link is drawn forwardly by this lip and lifted, its notch embraces the stirrup plate at the top of the slot therein and thus holds the link elevated by friction, and this holds back the movable clutch member 133, 15 enabling the hand operation by the hand wheel 410 as long as desired. A sufficient downward pressure, however, on the lip 418 releases this lock-out mechanism whenever desired. 20 To enable the delivery mechanism to operate without requiring the operation of the shearing mechanism so that the drum may be indexed idly (as for instance when composing "double-space" matter) I provide an extra key 450 at the side of the key-board (Fig. 1) which has a shank extending downwardly and connecting with the forward end of the lever 122 (Fig. 3). The connection of the lever 122 with the shearing key is 25 by a pin and slot as shown in Fig. 3, so that when the lever 122 is operated by the key 450, the shearing key is not operated thereby. This allows the dental clutch controlling the automatic indexing to be independently initiated whenever desired. 30 The indexing by the key 450 just described will ordinarily be done immediately following the delivery of a strip onto the blanket and before the subsequent strip is embossed. If, however, the operator delays the idle indexing until after he has embossed the subsequent line or a material portion of it, the toe 179 of the shoving plate 168 will stick in such embossed line or portion which 35 it cannot feed, the spring 170 yielding idly. To prevent damage to the machine in case such sticking occurs while the plate 168 is overlapping the embossing opening 18 I provide the safety mechanism shown in 40 Figs. 2, 4 and 5. This mechanism comprises a slotted link 420 loosely connected to the lever 166, which operates the plate 168, and pivoted at its other end to the lower end of a rock lever 421. The upper end 422 of this 45 lever extends adjacent to a collar 423 on the clutch operating rod 38. Ordinarily this lever portion 422 is held out of registration with the collar by a spring 424 as shown in Figs. 2 and 5. Now if the plate 168 should 50 stand in registration with the opening 18, then the lever 166 will pull the rod 420 toward the left in Fig. 2, rocking the lever 421 so that its upper end 422 stands in front of the collar 423. In such condition, when 55 the rocking plunger 30 on the die head rises

from engagement with the key lever and tends, through the bale, link and bell crank mechanism heretofore described, to withdraw the clutch rod, such operation is non-effective, because the clutch rod is locked. 70 Therefore the lower end of the bell crank 37 simply compresses a stiff spring 425 which, as shown in Fig. 4, positions a slideable head 426 into which the lower end of the bell crank 37 extends. Normally this 75 spring presses this head against a shoulder on the rod and the head acts unitarily with the rod to withdraw it when the bell crank is operated, but under the condition just described the spring forms a safety device preventing straining the parts. 80

My prior application referred to, shows a mechanism for loading delivered embossed strips onto a flat address plate. The present mechanism has been designed so that a somewhat similar device for holding a flat plate may be substituted for the drum 220. To enable this to be readily effected, I mount the drum shaft 221 in upwardly opening slots in the two standards, 230 and 231, and 90 I cover the shaft at these bearings by movable retaining plates 460 adapted to release it.

As shown in Fig. 7, each retaining plate 460 has a notch in its rear edge extending 95 beneath a screw 461 and has a slot 462 through which extends a clamp screw 463, which when loosened allows the plate to be slid forwardly to idle position. The sliding or removal of these plates enables the shaft, 100 with the drum and operating mechanism mounted on the shaft, to be readily removed from the standards and other mechanism substituted.

It will now be understood, from the given 105 description, that I have provided a mechanism adapted to be coupled with an embossing machine which produces embossed printing strips, and feed such strips onto a suitable receiving blanket, and that the mechanism is arranged to operate entirely automatically consequent upon the operation of the key which shears off the embossed line. As soon as such key is operated, the delivery mechanism described is initiated and 110 proceeds with its function independently of the operator, who may go on with the embossing of a subsequent line. The complete delivery of the embossed line, while sufficiently deliberate to operate smoothly, is effected well in advance of the time it will 115 take the operator to emboss a new line. Accordingly, his embossing operation proceeds without delay, and substantially as soon as he has embossed sufficient lines to constitute 120 a page form, the same are properly assembled on the blanket, and all that is necessary 125 is to release the blanket from the drum and it is ready for use in a suitable printing machine. While this mechanism is normally 130

entirely automatic, it allows for manual operation whenever desired.

Having thus described my invention, I claim:

5. 1. The combination with mechanism for embossing a printing strip, of mechanism for loading it into a page form. 70
10. 2. The combination of a mechanism for embossing printing strips and means for automatically assembling them consequent upon the completion of the embossed strip. 75
15. 3. The combination with means for embossing a flanged strip of metal and means for sliding said strip endwise into a holder, said holder being moved transversely whereby a plurality of strips are assembled therein. 80
20. 4. The combination with means for embossing a strip of metal, of means for flanging the edges thereof inwardly, and means for sliding such embossed and flanged strip onto an assemblage form. 85
25. 5. The combination with mechanism for embossing strips, of a keyboard having finger keys for operating said mechanism, and delivery mechanism actuated by a key in the keyboard. 90
30. 6. The combination with means for embossing printing strips, of means for assembling them into a form, and a keyboard having keys controlling the embossing and assembling means. 95
35. 7. The combination with embossing mechanism, of shearing mechanism and delivery mechanism initiated by the operation of the shearing mechanism and acting automatically during the period available for subsequent embossing. 100
40. 8. The combination with embossing mechanism, of a keyboard for controlling the same, shearing mechanism, delivery mechanism for the embossed material initiated by the operation of the shearing mechanism, and means whereby the keyboard is available for subsequent operation after the operation of the delivery mechanism has been initiated and before it has been completed. 105
45. 9. The combination with embossing mechanism, of a shearing mechanism, a key for operating the same, and a delivery mechanism initiated by the actuation of said key. 110
50. 10. The combination with embossing mechanism, of shearing mechanism, a key for controlling the shearing mechanism, a clutch caused to engage by the actuation of said key, and delivery mechanism controlled by said clutch. 115
55. 11. The combination of embossing mechanism, shearing mechanism, a keyboard having a key controlling the shearing mechanism, and means for assembling embossed and sheared strips into page form, said means operating automatically consequent upon the actuation of the shearing key. 120
60. 12. The combination with mechanism for embossing a strip, mechanism for shearing said strip, a keyboard having character keys controlling the embossing operation, a manually movable member controlling the shearing operation, means for supporting a form for holding a plurality of parallel lines, and mechanism for transferring the embossed and sheared strip to said form. 125
65. 13. The combination with embossing mechanism, of automatic means for causing an initial delivery of the material embossed, said means comprising a sliding plate, and shearing mechanism coupled therewith. 130
70. 14. The combination with a die holder having facing rows of male and female character dies with a longitudinal space between them, means for cutting off material occupying such space, and an automatically operated pusher plate adapted to move in said space and shove forward the material cut off. 135
75. 15. The combination of a suitable die holder having male and female dies with a space between them, means for supporting a strip of material in said space, a shearing die carried by the die holder, a keyboard, means operated thereby to actuate the character dies to emboss the strip, means for operating the shearing die to cut off the embossed portion, a pusher adapted to enter the space in the die holder, and automatic means for moving the pusher consequent upon the operation of the shearing mechanism. 140
80. 16. The combination of a shearing die, a reciprocating pusher, a key adapted to operate both the shearing die and the pusher to cause the latter to shove along the sheared strip. 145
85. 17. The combination of embossing dies, a shearing die, a keyboard having character keys for operating the embossing dies, and a key for operating the shearing die, a pusher, and mechanism operated automatically consequent upon the actuation of the shearing die to cause said pusher to engage the cut off embossed strip and shove it longitudinally. 150
90. 18. The combination with embossing mechanism, of an initial delivery mechanism comprising a sliding pusher, a clutch for operating it, and a shearing device adapted to cut off the embossed strip and cause the engagement of the clutch. 155
95. 19. The combination with means for embossing a strip, of a reciprocating hook adapted to draw the strip onto a form, and automatic means for operating the same controlled by operation of the embossing machine. 160
100. 20. The combination with means for embossing a strip, means for giving it an initial delivery movement, a reciprocating carriage having a hook, and means for causing

the hook to engage the rear end of the initially delivered strip and advance it.

21. The combination with means for embossing characters on a continuous strip, of means for shearing such strip, a pusher for advancing the embossed and sheared portion of the strip, a sliding carriage having a hook adapted to engage such advanced portion and further advance it, a clutch for controlling the two advancing means, and means controlled by the shearing mechanism for causing the clutch to engage.

22. The combination with a pair of delivery rolls, of a reciprocating member adapted to shove an embossed strip into the pass of said rolls, a member adapted to engage and advance the strip on the other side of said roll mechanisms for operating the two members respectively, and a single manually movable member for initiating both mechanisms.

23. The combination with a pair of coacting delivery rolls, mechanism to advance an embossed strip into the pass of the rolls, mechanism to receive the strip from the rolls, a clutch for controlling the operation of the two mechanisms mentioned, mechanism for cutting off the embossed portion of a strip for such delivery, and means for operating such shearing mechanism and for concurrently causing the engagement of such clutch.

24. The combination with a pair of coacting delivery rolls, of a reciprocating member to advance material into the pass of the rolls, a reciprocating member adapted to receive it from the rolls, a pair of cams for operating said two reciprocating members, a clutch for controlling said cams, and a manual device for causing the engagement of the clutch.

25. The combination with means for embossing a strip, of shearing mechanism therefor, a key for controlling the shearing mechanism, a clutch adapted to be engaged by said shearing key, to give a single rotation to a shaft, two cams on a shaft, a preliminary and a subsequent advance for the strip controlled by respective cams.

26. The combination with means for supporting and feeding a strip to be embossed, of embossing dies, a shearing die, a keyboard having keys for controlling the various dies, delivery rolls, a reciprocating member to advance the embossed and sheared strip into the pass of the rolls, a reciprocating member to receive the strip from the delivery rolls, a pair of cams for operating the respective members, and a clutch for controlling both cams engaged by the actuation of the shearing key.

27. The combination with embossing dies and means for actuating them, of a pusher adapted to shove forward the embossed strip, and a safety lock between the pusher

and the embossing mechanism preventing the actuation of the latter if the pusher stands between embossing dies which are in their active position.

28. In an embossing machine, the combination of embossing dies with a keyboard for actuating the same, means for supporting a strip of material to be embossed, a reciprocating pusher adapted to enter the space between dies and engage the rear end of the embossed strip and shove it along, and a safety interlock between the embossing mechanism and the reciprocating pusher preventing the actuation of the embossing mechanism if the pusher is between dies in active position.

29. The combination with means for delivering a printing strip, of a reciprocating hook adapted to engage the trailing end of the strip and move it along, and mechanism adapted to release the hook from such end strip and allow it to continue its travel beyond such end.

30. The combination, with means for embossing and delivering a printing strip, of a form holder adapted to receive strips in assembled form, a reciprocating carriage having a member to engage the trailing end of the strip and move it onto the form holder, and mechanism for releasing such member from the strip and allowing the carriage to continue its movement in the same direction.

31. The combination, with means for advancing a printing strip onto a holder for a plurality of such strips, of throw-out mechanism for the advancing mechanism controlled by the front end of the strip coming into definite position.

32. The combination, with means for holding a form to receive a plurality of strips, of means for advancing strips onto the form, a movable abutment adapted to be engaged by the front end of the advanced strip and moved thereby, and means whereby such movement causes the releasing of the advancing mechanism from the rear end of the strip enabling such advancing mechanism to continue its movement free from the strip.

33. The combination with means for holding a form holder to receive a plurality of strips thereon, means for shoving such strips lengthwise of the strip onto the holder, a movable member adapted to be engaged by the front end of the strip and operated thereby to release the advancing means from the rear end of the strip, and means for adjusting the position of said movable member.

34. The combination with means for holding a form holder adapted to relieve a plurality of strips, of means for advancing the strips thereon, means for stopping the advanced strip, and a lever and segment

for positioning the last mentioned means, whereby strips may be located in different positions from the edge of the holder.

35. In a delivery mechanism for printing strips, the combination of a hook adapted to engage the strip, a reciprocating carriage carrying the hook, means for rocking the hook, a reciprocating slide, a locking bolt adapted to connect the carriage with the slide, and mechanism for controlling said bolt.

36. In a delivery mechanism, the combination with means for holding a form holder, of a carriage mounted to reciprocate along the same, a rocking shaft in said carriage, a hook on the shaft adapted to engage a printing strip, a plate for rocking said shaft, a slide for rocking the plate and thereafter moving the carriage, and a locking bolt adapted to lock the carriage, plate and slide together.

37. In a delivery mechanism, the combination of a reciprocating carriage having a rocking hook, a slide for reciprocating the carriage, mechanism controlled by the slide for rocking the hook into engagement with the strip, a locking device to retain said engagement, a movable stop for the strip adapted to be engaged by the strip as it comes to position, and mechanism whereby said movable stop releases said lock.

38. In a delivery mechanism, the combination with means for supporting a form holder, of a reciprocating carriage adjacent thereto, a reciprocating slide, a rocking hook on the carriage, a connection between the carriage and slide for causing the hook to be rocked into engagement with the strip, the slide thereafter moving the carriage, a bolt for holding the hook in such engaged position, a stop adapted to be engaged by the strip as it comes into final position, a bar moved by said stop, a lever connected with the lock adapted to be engaged by said bar to withdraw the lock and enable the hook to swing free from the strip when the latter has come into position.

39. The combination, with means for supporting a flexible blanket in an arcuate form about an axis, of means for advancing printing strips onto the blanket, and mechanism for automatically turning the blanket about its axis consequent upon the placing of a strip thereon.

40. The combination, with means for embossing characters on a continuous strip and means for shearing such strip, of means for holding a flexible blanket in an arcuate form about an axis, mechanism operated automatically by the shearing means to advance a strip onto the blanket, and automatically actuated mechanism for thereafter giving the blanket a partial rotation about its axis to bring it into position to receive a new strip.

41. In a delivery mechanism, the combination of a shaft, a drum thereon adapted to hold a blanket, mechanism for indexing the drum comprising a collar on the shaft, a roller spring clutched against the collar, and a rocking plate carrying the roller.

42. The combination, with a guide for a printing strip and reciprocating means for advancing a strip along the same, of a shaft, a drum thereon, means for holding a strip receiving blanket on the drum, said blanket having rows of projections adapted to align with said guide, a member rockable about the axis of the drum to index it, and mechanism actuated by the return of the reciprocating advancing mechanism to rock said member to index the drum.

43. The combination, with means for holding a form adapted to receive a plurality of strips, of means for guiding the strips, mechanism for moving the form step by step to bring fresh holding means thereon into alignment with the guiding means, a reciprocating carriage having a member adapted to engage a strip on the guiding means and advance it onto the form and subsequently return for a fresh strip, and mechanism for moving the form step by step transversely of such delivery movement, said mechanism including a pair of coacting members, one connected with the strip and the other with the line advancer, and means whereby the line advancing member moves past the strip member idly in one direction of reciprocation and actively in the opposite direction.

44. The combination of a drum-like member adapted to hold a flexible blanket, a pin adapted to engage the rear face of the blanket, a spring pressing said pin outwardly, and a latch member coacting with the pin to hold it in inactive position free from the blanket.

45. The combination of a rotatable drum, means for holding thereon a blanket having recesses in its inner face, a substantially stationary support, a pin carried thereby slidably outwardly into engagement with one of such recesses, a spring pressing the pin outwardly, a latch pivoted on said support and having a cam shoulder engaging a projection on said pin, whereby the latch may cam the pin to idle position, and a spring tending to hold the latch in its idle position, whereby the pin may be active.

46. The combination with means for embossing printing members in the form of strips having inwardly turned flanges, a guideway and means for moving said strips from the embossing means along said guideway, a printing form on which such strips may be removably carried, and means for moving the strips onto the printing form from the guideway.

47. The combination with means for em-

bossing a continuous strip of metal, means for shearing the same at the end of an embossed line, a guideway, means for moving said strips from the embossing means along said guideway, a printing form on which such strips may be removably carried, and means operating automatically consequent upon the operation of the shearing mechanism for moving the strips onto the printing form from the guideway.

48. In combination, embossing mechanism for forming printing strips, a guideway leading therefrom, a printing form, means supporting said form adjacent the guideway, means on the form for receiving strips, and means for aligning the last named means with the guideway.

49. The combination, with embossing mechanism for forming printing strips, of a guideway leading therefrom, a printing form, means supporting said form adjacent the guideway, means on the form for receiving strips, means for aligning the last named means with the guideway, and means operating automatically consequent upon the completion of an embossed line for delivering the embossed strips onto said form.

50. The combination with mechanism adapted to form printing strips having inwardly turned flanges, of a printing form having projections for receiving said flanges to mount the strip thereon, a guideway and means for mounting the printing form with the holding means in alignment with said guideway.

51. The combination of means for embossing a printing strip, means for flanging the edges thereof, a guideway receiving such embossed and flanged strip, a printing form having means thereon for holding the printing strip, means for mounting the form to align the last named means with the guideway, and means for moving the printing strip along said guideway and onto said form.

52. The combination with means for forming and delivering embossed printing strips having inwardly turned flanges, of a guideway having flanges coacting therewith, a printing form having projections receiving said flanges of the strip, means for supporting the form to align said projections with the flanges of the guideway, and means for progressing the strip along said guideway and onto the form.

53. The combination with means for forming and delivering embossed printing strips having inwardly turned flanges, of a guideway having flanges coacting therewith, a printing form having a series of rows of aligned projections receiving said flanges of the strip, means for supporting the form to align said projections with the flanges of the guideway, and means for progressing the strip along said guideway and onto the form.

54. The combination with means for forming and delivering embossed printing strips, of a guideway having means coacting with the edges of the strip, a printing form having a series of aligned projections receiving said edges of the strip, means for supporting the form to align said projections with the flanges of the guideway, means for progressing the strip along said guideway and onto the form, and means acting automatically to shift the form transversely of the path of the strip.

55. The combination, with mechanism for embossing a continuous strip of metal, of mechanism for shearing it, a guideway for receiving the portion of the strip so embossed and cut off, a printing form having means for coacting with the sides of the strip and arranged for a plurality of lines, means for moving the strips from the guideway and onto said form, and means for advancing the form by step-by-step movement of present successive lines of strip holding means.

56. The combination with means for forming, embossing and delivering a printing strip having printing characters formed thereon, a guideway for supporting said strip, and means for moving the strip along the guideway, a printing form having a series of projections arranged in parallel rows to correspond to printing lines, said projections being adapted to engage and support the strips, means for supporting said form in alignment with the guideway, and means for latching the form with successive lines of projections in alignment with the guideway.

57. The combination of means for forming and delivering a printing strip to a printing form, said printing form having means for holding a series of strips in parallel lines, and means for moving the strips longitudinally on the form to initially position the same and adapted to move the same while on the form.

58. The combination with a means for embossing and delivering printing strips having flanges, of a form to receive said strips from the delivering means and having projections coacting with the flanges to hold the strips in parallel lines thereon, means for moving the strips to various locations on the form to position the same prior to printing.

59. The combination with means for delivering embossed printing strips, of a flexible form curved about an axis and adapted to receive the strips, means for moving the strips onto the form, means for supporting the form in position to receive the strips, means for removably securing the form in this position, and means for automatically causing a step-by-step partial rotation of the form consequent upon actuation of the strip moving means.

60. The combination of means for embossing a continuous strip, means for shearing the same, opposed continuously-rotated rolls adapted to deliver the embossed and sheared strip, a guideway adapted to receive the strip from the rolls, a rotative printing form, means for moving the strips from the guideway onto the form, and means for partially rotating the form, both of said means acting automatically consequent upon the 10 shearing of the embossed strips.
